Primary Examiner — Mark Goodwin

(57) **CLAIM**

The ornamental design for a dust collection drill and vacuum attachment, as shown and described.

DESCRIPTION

FIG. 1 is a front view of a dust collection drill and vacuum attachment showing my new design;

FIG. 2 is a rear view of the dust collection drill and vacuum attachment;

FIG. 3 is a left side view of the dust collection drill and vacuum attachment, a right side view being a mirror image thereof;

FIG. 4 is a top view of the dust collection drill and vacuum attachment;

FIG. 5 is a bottom view of the dust collection drill and vacuum attachment; and,

FIG. 6 is a top front side perspective view of the dust collection drill and vacuum attachment.
